UNITED STATES PATENT OFFICE

152,045

DESIGN FOR A COMBINATION TWIN WALKER AND STROLLER FOR CHILDREN

John R. Vibber, Kennewick, Wash.

Application July 11, 1947, Serial No. 140,223

Term of patent 7 years

(Cl. D14—3)

To all whom it may concern:

Be it known that I, John R. Vibber, a citizen of the United States, residing at Kennewick, in Benton County, and State of Washington, have invented a new, original, and ornamental Design for Combination Twin Walker and Stroller for Children, of which the following is a specification, reference being had to the accompanying drawing, forming a part thereof.

Figure 1 is a front perspective view showing the combination twin walker and stroller for children, and

Figure 2 is a rear perspective view of the same.

The characteristic features of my design reside in the portions shown by means of full lines in the drawings.

I claim:

The ornamental design for a combination twin walker and stroller for children, as shown and described.

JOHN R. VIBBER.
